UNITED STATES PATENT OFFICE.

CHARLES ALGERNON PARSONS AND JESSEL ROSEN, OF NEWCASTLE-UPON-TYNE, ENGLAND; SAID ROSEN ASSIGNOR TO SAID PARSONS.

DYNAMO-ELECTRIC MACHINE.

Application filed May 12, 1923. Serial No. 638,532.

To all whom it may concern:

Be it known that we, CHARLES ALGERNON PARSONS and JESSEL ROSEN, both subjects of the King of Great Britain and Ireland, and both residing at Heaton Works, Newcastle-upon-Tyne, in the county of Northumberland, England, have invented certain new and useful Improvements in and Relating to Dynamo-Electric Machines, of which the following is a specification.

The invention relates to the cooling of dynamo-electric machines and particularly to improvements in the cooling arrangements described in the British patent specification No. 15585 of 1914.

According to the invention therein described, a certain proportion of the air admitted to the end guards of a stator for the purpose of cooling the stator end windings passes directly to the outlet without effecting any cooling action and the main object of the present invention is to improve the efficiency of such an arrangement so as to obtain a greater degree of cooling per unit volume of cooling air supplied.

With this object the invention consists in the particular combination of elements hereinafter described and particularly pointed out in the claims.

Referring to the accompanying diagrammatic drawings:—

Figure 1 is a longitudinal section through a high-speed alternator embodying one form of the present invention, the section being taken on the line A—B of Figure 2, while

Figure 2 is a cross-section taken on the line C—D of Figure 1.

Figure 3 shows a sectional elevation on the line 3—3 of Figure 4 of as much of a dynamo as is necessary for explaining a modification of the invention,

Figure 4 being a corresponding cross-section on the line 4—4 of Figure 3; while finally

Figure 5 shows an elevation to a larger scale of one of the radial diverters.

The general course of the cooling air is indicated in the figures by arrows.

In carrying the invention into effect according to the illustrative form shown in Figures 1 and 2, cooling air is supplied by any suitable means such as a fan to the

ducts, *a*, and passes thence through the apertures, *b*, to the end windings. 55

The general arrangement of the ducts, *a*, for cooling the main body of the alternator is as described in the British patent specification No. 15585 of 1914, and does not need further description here. 60

As regards the cooling of the end windings, *c*, however, in order to prevent partial by-passing of the cooling air, the space in which they lie is divided into a number of cells by help of radial diverters, *e*, and circumferential diverters, *f*, arranged as shown so that each cell is supplied with cooling air through its appropriate aperture, *b*, and this air is compelled by reason of the disposition of the diverters to pass to the outlet 70 *k*, through the end windings lying in the particular cell concerned. The cells so formed may be arranged round, say, two-thirds of the circumference, the cooling air after passing through the end windings in 75 the manner described, entering the circumferential duct, *i*, whence it flows in the direction of the arrows in Figure 2 through the lower portions of the end windings external to the diverters to the outlet, *k*. 80

The diverters are preferably made of an insulating material on account of their proximity to the stator end windings which are at a high potential.

It will be seen that with the arrangement 85 described by-passing of the end windings by the cooling air is rendered impossible, all the air entering a particular cell being compelled to pass through the windings.

It will also be observed that the joints 90 between the windings, *m*, of the stationary armature which are embedded in a manner not unusual in the laminated core, *n*, and the end windings at which points maximum heating occurs, are very efficiently cooled, 95 as they are arranged directly in the path of the cooling air.

In order to reduce the amount of fitting required to adjust the radial and circumferential diverters to the stator end shields, 100 the form of the invention illustrated in Figures 3 to 5 may be adopted.

According to this form the stator armature, *o*, is wound with a two-layer winding of basket formation, the end windings, *p*, 105 running from a point in proximity to the

rotor outwardly at an angle as shown to a point of larger diameter so as to leave a space of wedge-shaped cross-section between the windings and the body, r , of the 5 stator casing.

Within this wedge-shaped space and at or about its maximum diameter, a circumferential diverter, s , is arranged passing, it may be, round the upper two-thirds of the 10 circumference, while the radial diverters, t , spaced at appropriate intervals are arranged so as to divide the remainder of the wedge-like space into cells each of which is supplied with air through an appropriate 15 aperture, u , in the manner described above in relation to the first form of the invention.

It will be seen that with such an arrangement, the fitting and adjustment of the 20 diverters are effected between the end wings, p , themselves and the body, r , of the stator casing and are thereby considerably simplified.

If desired, an additional section of circumferential diverter, s' , may be fitted 25 round about the lower third between the end windings and the stator end shields, v , at about the point of maximum diameter of such windings so as to re-direct the cooling air through the lower portion of the 30 end windings before it passes to the outlet.

The particular examples of the invention described above by way of illustration may be varied as regards the position of the 35 inlet and outlet to each cell and the position of the diverters to a considerable extent without exceeding the scope of the invention, while in addition, if desired, the flow of cooling medium may be reversed 40 so that what has been described as the outlet for each cell becomes the inlet, and vice versa.

Having now described our invention, what we claim as new and desire to secure 45 by Letters Patent is:—

1. In combination in a dynamo-electric

machine, stator end windings together with means for ensuring the passage of cooling air through said end windings, said means including radial and circumferential diverters, as set forth. 50

2. In combination in a dynamo-electric machine, stator end windings together with means for ensuring the passage of cooling air through said end windings, said means including radial and circumferential diverters forming walls of a series of cells, as 55 set forth.

3. In combination in a dynamo-electric machine, a stator body, stator end windings 60 and circumferential diverters located between said body and end windings, as set forth.

4. In combination in a dynamo-electric machine, a stator body, stator end windings 65 and circumferential and radial diverters located between said body and end windings, as set forth.

5. In combination in a dynamo-electric machine, a stator body having an end wall, 70 stator end windings running at an angle to said wall to form a wedge-shaped space and circumferential diverters located in said space, as set forth.

6. In combination in a dynamo-electric 75 machine, a stator body having an end wall, stator end windings running at an angle to said wall to form a wedge-shaped space and circumferential and radial diverters located in said space, as set forth. 80

7. In combination in a dynamo-electric machine, a stator having an end shield, stator end windings, means for directing cooling air through said end windings and a length of circumferential diverter located 85 between said windings and end shield to re-direct the air through another portion of said end windings, as set forth.

In testimony whereof we have signed our names to this specification.

CHARLES ALGERNON PARSONS.
JESSEL ROSEN.
